(57) **CLAIM**

The ornamental design for a chair, as shown and described.

DESCRIPTION

FIG. 1 is a right front perspective view of a first embodiment showing a chair according to the invention;

FIG. 2 is a right rear view of FIG. 1;

FIG. 3 is a right hand side view;

FIG. 4 is a front view of FIG. 1;

FIG. 5 is a left hand view;

FIG. 6 is a rear view of FIG. 1;

FIGS. 7 and 8 are respective top and bottom views of the chair of FIG. 1; and,

FIG. 9 is a right hand side view of a second embodiment which differs from FIG. 3 only in the side view of its back. The weave pattern schematically shown on the seat and backrest of the chair is continuous throughout.
